UNITED STATES PATENT OFFICE

2,282,901

ELECTRONIC APPARATUS

Harry C. Steiner, Scotia, and Eugene F. Peterson,
Schenectady, N. Y., assignors to General Electric Company, a corporation of New York

Application November 16, 1940, Serial No. 365,936

7 Claims. (Cl. 250—27.5)

The present invention relates to an improved cooling system for electronic power conversion apparatus.

For heavy duty operation of electronic devices such as arc-discharge rectifiers and the like it is desirable that artificial cooling be provided in order to maintain the operating parts within a safe range of temperatures. Liquid cooling has frequently been resorted to in this connection, but the difficulty of assuring a continuous supply of liquid cooling medium somewhat limits the applicability of this system. Forced air cooling avoids this limitation, but involves the further difficulty of requiring a considerable expenditure of power to maintain sufficient air-flow to dissipate large amounts of heat.

It is an object of the present invention to provide an improved forced-air cooling arrangement for electronic apparatus which arrangement will lessen the amount of power required by the air-supplying agency. In general, the means employed for the attainment of this object comprises the combination of a fan of the centrifugal type and an apparatus assembly which permits a large number of discharge devices to be positioned adjacent to the periphery of the fan and within the region of turbulence of the air discharged by it. This disposition of parts not only leads to a highly compact structural arrangement but also makes more efficient use of the fan output than appears possible with cooling arrangements heretofore employed.

A feature of the invention which is applicable in any system employing the combination of a number of discharge devices with voltage transformers for energizing them consists in the location of the transformers in a place in which they are exposed to the cooling effect of the stream of air being drawn into the fan casing. This may be done, for example, by establishing the axis of rotation of the fan in a vertical plane and positioning the transformer below and in proximity to the fan inlet (e. g. in the base structure which supports the fan).

The principles of the invention are illustrated in the accompanying drawings, in which:

Fig. 1 is an elevational view of one embodiment of the invention, part of the outer housing being broken away to show the internal arrangement of the parts;

Fig. 2 is a plan view of the embodiment illustrated in Fig. 1; and

Fig. 3 is a power conversion circuit which may be used with apparatus shown in Figs. 1 and 2.

Referring particularly to Figs. 1 and 2 there

are shown a plurality of metal enclosed discharge devices (numbered 10 to 15 inclusive) which are located in a circular grouping. Only the exterior aspect of the devices appears in the drawings but it is assumed that each device is suitable for power conversion purposes. In this connection, each device may comprise, for example, a power rectifier of the type which includes an anode, a mercury pool cathode and a control member for regulating the initiation of a discharge between the anode and cathode. For the latter purpose one may employ, for example, an immersion starting electrode.

In the apparatus illustrated the cathode connection of each discharge device comprises a heavy metal stud (parts 10', 13' and 14') depending from the bottom of the device envelope, and the corresponding anode connection comprises a heavy flexible lead (10" to 15") insulatingly sealed through the top wall of the device. Connections for the control elements of certain of the devices are indicated at 17, 18 and 19. All the devices are provided with extended heat-exchange surfaces in the form of externally projecting circular fins 20 which facilitate the dissipation of heat. In order to promote selective cooling of the lower portion of each device and thus to permit its anode to maintain a higher temperature than the cathode, the upper fins are more widely spaced than those at the bottom of the envelope.

The space around which the various discharge devices are grouped is occupied by a centrifugal fan identified as a whole by the numeral 24. This comprises a plurality of appropriately curved vanes 25 arranged in a cage-like formation and is adapted to receive air at a region adjacent the axis of the fan and to discharge such air at its periphery. An electric motor 27 having a vertically depending shaft 28 is secured to the fan 24 and, when energized, drives the fan at an appropriate operating speed.

The fan 24 is enclosed by the provision of wall structure which, in combination with the discharge devices 10—15 defines a substantially complete chamber. The wall structure may consist, for example, of a plurality of sheet metal parts 30 to 35 which are so bent as to define radial ducts containing the various discharge devices. Top and bottom walls 40 and 41 serve to complete the fan enclosure. The upper wall 40 of the fan chamber provides a support for the motor 27, which is secured to the wall through a mounting plate 43 and a plurality of rigid posts 44. Escape of air from the chamber around the

motor shaft 28 is prevented by means of a suitable packing arrangement indicated at 47. The bottom wall 41 of the fan chamber has a central opening which permits a continuous flow of air into the fan.

It is apparent that as a result of the arrangement described, air can escape from the fan chamber only by passage in proximity to the discharge devices 10 to 15. The location of the devices at points relatively close to the periphery of the fan further assures that each device shall be within the region of turbulence of air discharged by the fan. Tests show that extremely effective heat exchange is obtained under these circumstances and that for a given flow of air, a much greater degree of cooling can be realized than would be possible, for example, by arranging each device at the end of a long air duct or the like. In addition, the symmetrical arrangement of the various devices with respect to the fan, as well as the nature of the fan itself, permits an extremely compact construction of the apparatus as a whole. This facilitates the use of the apparatus in factories and in other locations where space is at a premium and also increases the practicability of moving the apparatus from place to place in cases where mobility is desired.

In the normal use of discharge apparatus of the character described in the foregoing, say, for purposes of rectification or inversion, a considerable amount of auxiliary equipment is necessary. With a structural arrangement such as that shown, this auxiliary equipment may be readily included in the apparatus assembly without increasing the space occupied thereby. For example, the transformers needed for supplying power to the various discharge devices may be located in the base structure by which the apparatus assembly is supported. The essential features of a typical arrangement of this kind are shown in Fig. 1 in which the posts 50 and 51 are assumed to constitute elements of the mounting structure of the electronic apparatus. Within the space between the posts 50 and 51 there is provided a housing 53 which serves jointly as a duct for supplying air to the fan inlet and as a housing for a plurality of transformers serving for the energization of the discharge devices. One such transformer is illustrated at 55 and is shown as including a plurality of externally projecting vanes 56 which facilitate the transfer of heat between the transformer and the air flowing through the housing 53. By this means a single air-impelling agency (i. e. the fan 24) is caused to serve for cooling both the discharge devices and the power supply apparatus.

The various transformers enclosed by the housing 53 may be connected with the discharge devices by means of insulated conductors extending upwardly through the free spaces provided within the wall parts 30 to 35. This is exemplified by the conductor 58 which connects with the anode lead 10" of the discharge device 10. It is customary in apparatus of the type under consideration to provide a fuse link or similar safety device in circuit between the transformer and its associated discharge device. This is conveniently accomplished in the present instance by the provision at the top of the apparatus assembly of a hexagonal panel board 60 upon which a number of fuses (exemplified at 61, 62, and 63) are mounted in proximity to the various discharge tubes.

The operation of discharge devices of the character described above ordinarily requires the

use of firing tubes and associated circuit equipment in connection with the control elements of the devices. All this auxiliary equipment may be readily mounted within the compartments 5 formed by the convolutions of wall parts 30 to 35. This possibility is illustrated by tubes 68, 69 and 70 which are shown within certain of the compartments together with schematically indicated auxiliary elements 71, 72 and 73. For the sake of simplicity the connections between the tubes 68-70 and the main discharge devices are not shown.

The electrical aspects of a typical power conversion apparatus of the character illustrated in Figs. 1 and 2 are shown in Fig. 3. In this figure there are illustrated a plurality of electric discharge devices 10 to 15, these being assumed to correspond in essential particulars to the similarly numbered devices of Fig. 1. The devices are used to transmit energy from a polyphase alternating current supply circuit 75 to a direct current load circuit 76. To this end, the supply circuit 75 is connected with the primaries 78, 79, 80 of a plurality of transformers connected in delta. Each of the transformers is assumed to be provided with a pair of secondary windings (78' and 78'', 79' and 79'' and 80' and 80''), these secondaries being connected in a double Y arrangement as shown. The neutral points of the two Y's are connected through an interphase reactor 83 to produce a six-phase system. The midpoint 84 of the reactor 83 is connected to one side of the direct current circuit 76 while the other side of the direct current circuit is connected in common to the cathodes of devices 10 to 15. The terminals of the various secondary windings are connected with the anodes of the devices through appropriate fuse links indicated at 86 to 91 inclusive.

The operation of the various discharge devices is controlled by the starting electrodes associated with the devices, and it is assumed in this connection that each of the illustrated starting electrodes is connected to an appropriate control circuit. (Since the control circuits obviously form no part of the present invention, they are not specifically illustrated.) By means of the control circuits, the various discharge devices are caused to conduct intermittently and sequentially in such fashion as to supply a rectified potential to the terminals 76.

The foregoing description of Fig. 3 illustrates the diverse character of electrical apparatus which may be advantageously incorporated in a structural arrangement such as that illustrated in Figs. 1 and 2. It will be observed in this connection that all the elements of the circuit of Fig. 3 are represented in their structural counterparts in the apparatus shown in Fig. 1.

While the invention has been described by reference to a particular embodiment thereof, it will be understood that numerous modifications may be made by those skilled in the art without departing from the invention. We therefore aim in the appended claims to cover all such equivalent variations as come within the true spirit and scope of the foregoing disclosure.

What we claim as new and desire to secure by Letters Patent of the United States is:

1. An improved arrangement for electronic power conversion apparatus comprising a plurality of electronic discharge devices grouped around a given center, a centrifugal fan having its axis of rotation at least approximately coin-

cident with said center, structure cooperating with said discharge devices to define a generally cylindrical chamber enclosing the fan, the chamber being formed to assure that air discharged by the fan shall escape from the chamber mainly by passage in proximity to the discharge devices, and an inlet to the chamber for maintaining a supply of air to the fan.

2. An improved arrangement for electronic power conversion apparatus comprising a fan of the centrifugal type, wall structure defining a generally cylindrical chamber enclosing the fan, said chamber having a plurality of openings disposed about the periphery of the fan and permitting the escape from the chamber of air discharged by the fan, a plurality of electronic discharge devices respectively disposed in and incompletely filling the said openings, the said discharge devices being in sufficient proximity to the periphery of the said fan to be within the region of turbulence of air discharged by the fan, and means for supplying air to the fan to maintain continuous cooling of the discharge devices.

3. An improved arrangement for electronic power conversion apparatus comprising a fan of the centrifugal type, means defining a cylindrical chamber enclosing the fan and providing a plurality of radial ducts for permitting the escape of air discharged by the fan, a plurality of electric discharge devices respectively disposed in and incompletely filling the said ducts, and an inlet to the chamber for supplying air to the fan so as to maintain continuous cooling of the discharge devices.

4. An improved arrangement for electronic power conversion apparatus comprising a fan of the centrifugal type, means defining a cylindrical chamber enclosing the fan, said chamber having a plurality of peripheral openings therein for permitting the escape from the chamber of air discharged by the fan, a plurality of metal enclosed electronic discharge devices respectively positioned in the various openings and incompletely filling the same, extended heat-exchange surfaces respectively connected with the containers of the several discharge devices, and means for supplying air to the fan to effect continuous cooling of the said heat-exchange surfaces.

5. An improved arrangement for electronic power conversion apparatus comprising a fan of the centrifugal type having its axis of rotation

in a vertical plane, wall structure defining a chamber enclosing the fan, said chamber having a plurality of openings disposed about the periphery of the fan and permitting the escape from the chamber of air discharged by the fan, a plurality of electronic discharge devices respectively disposed in and incompletely filling the said openings, a motor supported on the upper wall of the said chamber for driving the said fan, and means for supplying air to the fan through the lower wall of the chamber to effect continuous cooling of the discharge devices.

6. An improved arrangement for electronic power conversion apparatus comprising a fan of the centrifugal type, means defining a cylindrical chamber enclosing the fan, said chamber having a plurality of peripheral openings therein for permitting the escape of air discharged by the fan, a plurality of electronic discharge devices respectively positioned in the various openings and incompletely closing the same, whereby the devices are cooled by air discharged through the openings, a voltage transformer connecting with at least certain of the discharge devices for energizing the source, said transformer being located adjacent to the fan-enclosing chamber, and an air inlet for the chamber positioned to assure that air supplied to the chamber shall initially pass in heat-exchanging relation with the transformer.

7. An improved arrangement for electronic power conversion apparatus comprising a centrifugal fan having its axis of rotation in a vertical plane, means defining a cylindrical chamber enclosing the fan, said chamber having a plurality of peripheral openings for permitting the escape of air discharged by the fan, a plurality of electronic discharge devices respectively positioned in the said openings and incompletely closing the same, whereby the devices are cooled by air passing through the openings, a base structure supporting the said fan and discharge devices, a voltage transformer located within the said base structure and electrically connected with at least certain of the said discharge devices for energizing them, and means for causing air for cooling the said discharge devices to flow sequentially over the said transformer and into the lower end of the fan-enclosing chamber.
